UNITED STATES PATENT OFFICE.

EDWIN L. UPSON, OF BROOKLYN, NEW YORK, AND HENRY W. PLEISTER, OF WESTFIELD, NEW JERSEY, ASSIGNORS TO HENRY B. NEWHALL, OF PLAINFIELD, NEW JERSEY.

DRILL-ROTATING MECHANISM FOR PERCUSSION-HAMMERS.

1,163,712.

Specification of Letters Patent. Patented Dec. 14, 1915.

Application filed April 3, 1913. Serial No. 758,656.

To all whom it may concern:

Be it known that we, EDWIN L. UPSON, a citizen of the United States, residing at Brooklyn, in the county of Kings and State 5 of New York, and HENRY W. PLEISTER, a citizen of the United States, residing at Westfield, in the county of Union and State of New Jersey, have invented certain new and useful Improvements in Drill-Rotating 10 Mechanism for Percussion-Hammers, of which the following is a specification.

Our present invention relates to an improvement in cutter or drill rotating mechanism as applied to percussion hammers of 15 the type described in our co-pending application, Serial No. 719,735, filed Sept. 11, 1912. One important advantage of the application of this rotating means to percussion drills of the above noted type, is that 20 the cutter or drill is rotated a certain predetermined amount simultaneously with each revolution of the cam disk, thereby increasing the efficiency of the cutting or boring capacity of the tool when in use as a rock 25 drill.

In the accompanying drawing, Figure 1 is a sectional view of a portion of our device taken on the line 1—1 of Fig. 2; Fig. 2 is a sectional view taken on line 2—2, Fig. 1, 30 looking in the direction of the arrows; and Fig. 3 is a sectional view on line 3—3, Fig. 1.

In Figs. 1 and 2 there is shown enough of the important elements of our device to indicate the application of the improvement. 35 The cam or actuating disk 8 is rotatably mounted upon a main bearing shaft 2, which is suitably supported in a housing 3, and which is shown broken away in Fig. 2. The said housing has a tubular extension 4 in 40 which is arranged a reciprocating cylindrical hammer 5. The said hammer has at its upper end a slot 6 which is arranged in such a manner as to be in the path of the cam extensions 7 that are arranged on the 45 rotating disk 8, and as the said cams 7 pass through the said slot they cause the hammer to be lifted upwardly. When the said cam has left the slot, the hammer is then free to be forced downwardly under the tension of a spring member 9, which is in engagement with the upper end of the said hammer at one end and attached to a portion 50 of the housing wall, as at 10, at its

other end by such suitable means as a stud 11, as indicated in Fig. 1.

Arranged at the lower end of the tubular extension 4 is a suitable collet or chuck 12 which has arranged therein a tapered aperture 13 which maintains therein a suitable cutting tool 14; in the present instance shown as a stone cutting drill. The upper end of this chuck 12 is flanged as at 15 and is in rotatable engagement with the walls of the chamber 16 formed at the lower end of the extension 4. A threaded lock-nut or 65 bushing 17 is arranged in such a manner in the lower part of the extension 4 as to maintain the said collet 12 in operative alignment with the hammer 5 and at the same time permit a slightly limited motion therein, as indicated by the clearance 18.

An extension of the aperture 13 at the upper end of the collet 12 is arranged in a tapered rectangular manner as indicated at 19, to engage with a square faced tapered 75 shank portion 20 of a driving shaft 21 which extends down through the center of the hammer 5, the upper end of the said shaft being suitably mounted for rotation in a bearing block 22, said shaft having arranged adjacent the said block a driven bevel gear 23, and on the opposite side of said bearing a retaining collar 24. It will be noted that the shaft 2 is formed in such a manner as to be an extension of the said bearing block 22, 80 as indicated in Fig. 3, and at the end opposite to the said shaft, is arranged a threaded stud portion 25, so that in assembling the hammer the said bearing supports the rotating disk 8 and the drill rotating shaft 21 in 85 proper working alignment by reason of being attached to the back wall of the housing 3 by means of the said threaded stud portion and a lock-nut 26. Arranged on the said driving disk 8, either cast or otherwise secured thereon, is a driving bevel gear 27 corresponding with and adapted to drive the driven gear 23, and as indicated in Figs. 1, 2 and 3, this bevel gear is in driving engagement with the first mentioned bevel gear 23, so 90 that when the disk 8 is rotated by a hand crank or any other suitable means, not shown, but which may be suitably affixed to the hub portion 28 of the said disk 8, the shaft 21 is caused to rotate and at the 95 same time the hammer is retracted and re-

leased by the cams 7 on the said disk 8, thereby slowly rotating the drill and at the same time causing the hammer to operate to strike the drill through its attached holding 5 bushing or collet 12.

In use, the tool is pressed against the work and the shaft 21 and chuck 12 are angularly firmly engaged, and rotate as one piece; but whenever a blow is struck they are slightly 10 separated by the advance of the chuck and tool and the recoil of the housing 3 and shaft 21. If the taper of the engaging chuck socket and shaft head be sufficient, such separation gives to the chuck and tool therein 15 a "dwell" sufficient to cause the said tool to function properly. It will be noted that such tapered engagement has the practical utility of an intermittent gearing between the cam disk and the chuck; and that the 20 shaft 21, owing to its being held in alinement by the bushing 12 and the bearing block 22, acts as a slide bar and guide for the reciprocating hammer member 5.

While not necessary, it is sometimes desirable 25 to have the intermittent stop period coincide with the moment of impact of the hammer with the cutting drill which obviously can be accomplished by changing the timing of the angular head 20, the portion 30 19 of the collet 12, and the gears 23 and 27 relative to one another. It is also advantageous, in cutting stone, to arrange that the degree of rotation of the drill varies each 35 revolution in such a manner as to preclude, in the well known type of four lipped drill, the striking of the drill points at the same position at each revolution which likewise can, with facility, be accomplished by properly changing the timing of the angular 40 head 20, the portion 19 of the collet 12, and the gears 23 and 27 relative to one another. This latter arrangement, in other words, would cause the drill to cut at a different angular degree in the second revolution 45 than it did in the first revolution, and this change of cutting contact is progressive or retrogressive accordingly as the drill makes more than a complete rotation or less than a complete rotation between successive 50 hammer impulses.

The above noted change of cycle of drill may be regulated by having different pitch diameters of the operating gears, as in hunting tooth gears, and as may be ascertained 55 by comparing those (23 and 27) shown in Fig. 2. For instance, as there are six cams on disk 8, there might be twelve teeth on gear 23, and only eleven teeth on gear 27. This arrangement would therefore cause the 60 loss of degree of revolution of the drill equal to one tooth each revolution. Conversely, if gear 27 had twelve teeth and gear 23 eleven

teeth, the drill would be correspondingly advanced one tooth each revolution, and this differential variation of rotation would 65 prevent the impact of the drill occurring at the same spot in successive revolutions.

Having thus described our invention, we claim:—

1. A housing; a tubular extension thereof 70 on a percussion axis and terminating in a chuck mounting; revolvably mounted with axial play therein, a tool-chuck formed with an axial, tapered engagement socket; a hammer operable in said extension to strike said 75 chuck, means for intermittently retracting said hammer, a shaft rotatably mounted in said housing and thereon a tapered, terminal head adapted to engage and rotate said chuck; a gearing operably connecting said 80 shaft and retracting means to rotate said chuck.

2. A housing, a tubular extension thereof terminating in a chuck mounting, a tool-chuck revolvably mounted in said housing 85 with axial play, a hammer operably mounted in said extension to strike said chuck, means operatively connected to intermittently retract said hammer, means for maintaining a chuck-striking tension on said hammer, a shaft revolvably mounted in said housing, gearing connecting the upper end of said shaft with said retracting means, and an angular head at the lower end of said shaft, there being an angular socket in said 90 chuck to be engaged by said angular head by means of which the chuck will be rotated by said shaft.

3. A housing, a tubular extension thereof and terminating in a chuck mounting, a tool-chuck revolvably mounted in said housing, a shaft extending through said housing, a tubular hammer operably mounted in said extension to strike said chuck, means loosely mounted on said shaft and operatively connected to intermittently retract said hammer, means for maintaining a chuck-striking tension on said hammer, a second shaft extending through said tubular hammer and revolvably mounted therein, the upper end 105 of said second shaft being operatively connected with said retracting means to be rotated thereby, and an angular head at the lower end of said second shaft, there being an angular socket in said chuck to be engaged by said angular head by means of which the chuck will be rotated by said second shaft.
